UNITED STATES PATENT OFFICE.

GEORGE H. BLAKE, OF ALAMEDA, CALIFORNIA.

FOLDING SLEEPING-COT ESPECIALLY ADAPTED FOR AUTOMOBILES.

1,372,117.

Specification of Letters Patent.

Patented Mar. 22, 1921.

Application filed April 1, 1920. Serial No. 370,382.

To all whom it may concern:

Be it known that I, GEORGE H. BLAKE, a citizen of the United States, residing at Alameda, in the county of Alameda and 5 State of California, have invented certain new and useful Improvements in Folding Sleeping-Cots Especially Adapted for Automobiles, of which the following is a specification.

10 My invention relates to folding sleeping-cots especially adapted to be carried, when folded, upon automobiles.

The objects of my invention are: first, to provide a substantial but light cot which 15 may be used as a bed entirely independent of the automobile upon which it is carried; and second, to so construct such a cot that it can be folded into proper size to be carried upon an automobile, and when so 20 folded and secured to the automobile, that it can be used, in connection with the running board, as a luggage carrier. By this construction I am enabled to make a cot of sufficient size and strength for two persons to lie 25 upon with comfort, and which can be quickly and easily folded, to occupy comparatively little space.

With these objects in view my invention will now be more fully described with reference to the accompanying sheets of drawings, 30 wherein I have shown a single cot adapted for the use of one person only. It is to be understood, however, that by merely increasing the lateral dimensions of its parts, 35 the cot may be adapted for occupancy by two persons. In said drawings:

Figure 1 is a perspective view of my cot, reduced in size, folded and secured to the running board of an automobile.

40 Fig. 2 is a partly broken plan of the same, in extended position, taken approximately on the line 2-2 of Fig. 3.

Fig. 3 is a partly broken side elevation, taken on the line 3-3 of Fig. 2.

45 Fig. 4 is a partly broken plan view showing my cot partly folded.

Fig. 5 is a partly broken side elevation showing my cot partly folded as in Fig. 4.

Fig. 6 is an end elevation of my cot extended.

50 Fig. 7 is an end elevation showing my cot folded and attached to the running-board of an automobile.

Fig. 8 is a partly broken side elevation, 55 enlarged, of one end portion of my cot, extended.

In the drawings, the reference numeral 1 designates the main frame of my cot, which is preferably constructed of angle iron, and bent into the form of a rectangle.

60

Inside this frame is stretched a fabric 2, Figs. 1 and 2, of articulated wires or other suitable material, connected with said frame at its edges by springs 3 in the usual manner. The frame 1 is divided longitudinally at its center, as shown at 4, Figs. 2 and 4, and the two halves are pivotally connected by pins or rivets 5, Figs. 2, 3, 6, 7 and 8.

65

The frame 1 is adapted to be supported, when extended, upon legs 6 and 7. The 70 legs 6 of which there are preferably three on each side, are pivotally secured to the side members of the frame at 8, Figs. 2, 3 and 8, and are adapted to fold up toward and lie parallel with said frame side members, as 75 shown in Fig. 5. The legs 7 are located one at each end, and are pivotally secured to the hinge pins 5 of the frame, as shown in Figs. 3, 6, 7 and 8. All of said legs 6 and 7 are preferably formed of angle iron.

80

The side legs 6 are held in extended position by diagonal braces 9, Figs. 3, 5, and 8 which are pivotally connected with the side frame members at 10, and are adapted to hook over pins 11 projecting from said legs 85 6. Said braces 9, when unhooked from the legs 6, fold up into the angle of the frame 1 as shown in Fig. 5.

85

The end legs 7 are permanently connected by a longitudinal bar 12, Figs. 2, 3, 4, 5 and 90 8, preferably formed of angle iron, and extending the entire length of the cot at a sufficient distance below the bed-fabric 2 to permit the latter to have free play. Permanent diagonal braces 13 extend between 95 said bar 12 and the upper portions of the end legs 7.

90

The end legs 7 are further braced to the end portions of the frame 1 by diagonal braces 14, Figs. 3, 5, 6, 7 and 8. These braces 100 14 are arranged in pairs, one pair being situated at each end of the frame 1. Each member of the pair is pivotally connected with the end portion of the frame 1 at 15, and the two members are pivotally connected 105 together at 16, but are entirely free from the end leg 7 except when the frame 1 is fully extended, in which position the angle of the V formed by said braces bears against a stop pin 17, and locks under the head thereof, as 110 shown particularly in Fig. 6. When the frame 1 is folded, the diagonal braces 14

automatically move downward away from the pin 17, and occupy the position shown in Fig. 7, the end leg 7 lying parallel with and between the end portions of the frame 1.

5 The central longitudinal bar 12 is secured to the four side legs 6 located nearest the ends of the cot by means of braces 18, Figs. 2, 3, 4, 5 and 8, pivotally connected with said bar at 19, Figs. 2, 3 and 5, and adapted 10 to hook over pins 20, Figs. 2 and 8, projecting from said legs 6. When unhooked from said legs, the braces 18 are adapted to swing horizontally to lie parallel with the bar 12 as shown in Figs. 4 and 5. Said braces 18 have no vertical movement, the spring of the metal being sufficient to allow their ends to be hooked upon the pins 20.

15 The longitudinal bar 12 is further braced to the central pair of side legs 6, by means of a transverse bar 21, Figs. 2, 3, 4, 5 and 6, preferably formed of angle iron. Said transverse bar 21 is pivotally connected at its center 22, with the longitudinal bar 12, and its ends are adapted to be hooked 20 over pins 23, Fig. 2, projecting from the central pair of side legs 6, the spring of the various parts being sufficient to permit such connection. When the ends of said transverse bar 21 are unhooked, the bar may be 25 swung horizontally, about its central pivot 22 to lie parallel with the longitudinal bar 12, as shown in Figs. 4 and 5.

30 Diagonal braces 24, Figs. 2, 6 and 8 are pivotally connected at 25, with the central pair of side legs 6, near their upper ends, and are adapted to be hooked over pins 26, Figs. 2 and 6, projecting from the transverse bar 21. When unhooked from said bar, said braces 24 may be swung parallel 35 with said legs 6. A short leg 27, Figs. 3, 5 and 8, is permanently secured to the central portion of the longitudinal bar 12 for supporting the same.

35 In order to fold the cot, the transverse braces 18 and 21 are first swung parallel with the longitudinal bar 12; the side legs 6 and their braces 9 are then folded to lie against the side portions of the frame 1; and finally the two side portions of the frame 1 40 are folded together, to occupy the positions shown in Figs. 1 and 7.

45 It will be seen that the cot, when extended, is amply supported by the legs 6, 7 and 27, and is so braced by the various diagonal and other members as to be perfectly rigid, and yet may be easily and quickly folded to such a size as to be readily carried about, or stored in a small space.

50 For attaching the folded cot to an automobile, as shown in Figs. 1 and 7, I provide hooks, one of which is shown at 28, Fig. 7, and is adapted to be secured to the outer edge of the running-board 29 of the automobile by a coöperating clamping member 30, 55 the members 28 and 30 being clamped to-

gether by a bolt 31. Any desired number of said hooks 28 may be secured to the edge of the running-board. The inner side portion of the frame 1 of the folded cot rests upon and is firmly held by said hooks. Eyes 32, 70 formed in the upper ends of the end legs 7, above the pivot pins 5, are adapted to be engaged by hooks 33, secured to the ends of straps 34, Fig. 1, which may be fastened in any desired manner to convenient parts of 75 the automobile body 35.

The folded cot therefore rests in a position substantially parallel with the automobile body and extending upwardly from the outer edge of the running-board 29, as shown 80 in Fig. 1. The space between the cot and the automobile body may then be conveniently used for the reception and carrying of luggage. The longitudinal bar 12 of the cot, not shown in Fig. 1, forms a rigid support 85 throughout its entire length, so that the bed fabric 2 will not bulge outwardly under the lateral pressure of the luggage carried between it and the automobile body 35.

When it is desired to remove the cot from 90 the automobile, the straps 34 and hooks 33 are first freed from the cot, and it is then swung outwardly and downwardly, this movement automatically permitting its lower edge to be lifted from the running-board 95 hooks 28; or if it is desired to extend the cot upon its removal from the automobile, the outer half of the frame 1 is first swung upwardly into its extended position, thus giving convenient access to the legs and 100 braces, which are then extended and adjusted; and finally the straps 34 and hooks 33 are released, and the fully extended cot is lowered on to its legs and lifted off the running-board hooks 28.

105 I claim:—

1. A folding cot comprising a substantially rectangular frame divided into two portions; a yieldable bed fabric supported by said frame; hinged joints between the two portions of said frame whereby said two portions may be folded together; a plurality of side legs pivotally connected with said frame and adapted to be folded to lie parallel therewith; a pair of end legs, pivotally connected with said frame at the hinged joints thereof; and a pair of diagonal braces positioned at each end of the frame, the members of each pair being pivotally connected with said frame on each side of the hinged joint thereof, and said members being pivotally connected together and removably associated with the end leg. 115

2. A folding cot comprising a substantially rectangular frame divided longitudinally into two portions; a yieldable bed fabric supported by said frame; hinged joints between the two portions of said frame whereby said two portions may be folded together; side legs pivotally con- 125 130

nected with said frame and adapted to be folded to lie parallel therewith; a pair of end legs, pivotally connected with said frame at the hinged joints thereof; and a 5 longitudinal member extending between and rigidly connecting said end legs.

3. A folding cot comprising a substantially rectangular frame divided longitudinally into two portions; a yieldable bed fabric supported by said frame; hinged joints between the two portions of said frame whereby said two portions may be folded together; side legs pivotally connected with said frame and adapted to be 10 folded to lie parallel therewith; a pair of end legs, pivotally connected with said frame at the hinged joints thereof; a longitudinal member extending between and rigidly connecting said end legs, and foldable 15 braces extending between said longitudinal member and said side legs.

4. A folding cot comprising a substantially rectangular frame divided longitudinally into two portions; a yieldable bed fabric supported by said frame; hinged joints between the two portions of said frame whereby said two portions may be folded together; side legs pivotally connected with said frame and adapted to be 20 folded to lie parallel therewith; a pair of end legs, pivotally connected with said frame at the hinged joints thereof; a longitudinal member extending between and permanently connecting said end legs, foldable 25 transverse braces extending between said longitudinal member and said side legs; and foldable diagonal braces extending between the frame and said side legs.

5. A folding cot comprising a substantially rectangular frame divided longitudinally into two portions; a yieldable bed fabric supported by said frame; hinged joints between the two portions of said frame whereby said two portions may be 30 folded together; side legs pivotally connected with said frame and adapted to be folded to lie parallel therewith; a pair of end legs, pivotally connected with said frame at the hinged joints thereof; a longitudinal member extending between and permanently connecting said end legs, foldable 35 transverse braces extending between said longitudinal member and said side legs; and a pair of diagonal braces positioned at 40 each end of the frame, the members of each pair being pivotally connected with said frame on each side of the hinged joint thereof and said members being pivotally

connected together and removably associated with the end leg. 60

6. A folding cot especially adapted for separable connection with the running board of an automobile, comprising a substantially rectangular frame divided longitudinally into two portions adapted to be folded parallel with each other; a yieldable bed fabric supported by said frame; legs for supporting said frame; a hook permanently connected with the automobile running board, said hook being adapted to freely receive one longitudinal side member of said frame when the latter occupies a substantially horizontal position, and to engage and retain said side member to prevent separation thereof from said hook when the frame occupies a substantially vertical position; and means for retaining said frame in a substantially vertical position. 70

7. A folding cot especially adapted for separable connection with the running board of an automobile comprising a substantially rectangular frame having a side member with a profile of greater height than width; a bed fabric carried by said frame; a hook permanently mounted upon 80 the automobile running-board, said hook having its open side uppermost and being adapted to freely receive the said frame side members when the frame occupies a substantially horizontal position, and to engage and 85 retain said side member to prevent separation thereof from said hook when the frame occupies a substantially vertical position; and means for retaining said frame in a substantially vertical position. 90

8. A folding cot especially adapted for separable connection with the running board of an automobile, comprising a substantially rectangular frame formed of angle iron; a bed fabric carried by said frame; a hook permanently mounted upon the automobile running-board, said hook having its open side uppermost and being adapted to freely receive one side member of said frame when the frame occupies a substantially horizontal position, and to engage and retain said side member to prevent separation thereof from said hook when the frame occupies a substantially vertical position; and means for retaining 100 said frame in a substantially vertical position. 105

In testimony whereof I have signed my name to this specification.

GEORGE H. BLAKE.
